UNITED STATES PATENT OFFICE.

ALOYSIUS W. BECKER, OF CHICAGO, ILLINOIS.

DESIGN FOR A SPACE HEATER.

Application filed December 17, 1928. Serial No. 29,295. Term of patent 14 years.

To all whom it may concern:

Be it known that I, ALOYSIUS W. BECKER, a citizen of the United States, and a resident of Chicago, Cook County, Illinois, have invented a new, original, and ornamental Design for Space Heaters, of which the following is a specification.

The figure is a perspective view of a space heater, showing my new design.

I claim:

The ornamental design for a space heater, as shown.

ALOYSIUS W. BECKER.
